UNITED STATES PATENT OFFICE.

ALBÉRIC LOUIS CHOPIN, OF PARIS, FRANCE.

PERCUSSION-DRILL.

1,330,171.

Specification of Letters Patent. Patented Feb. 10, 1920.

Original application filed January 26, 1917, Serial No. 144,783. Divided and this application filed March 25, 1918. Serial No. 224,620.

To all whom it may concern:

Be it known that I, ALBÉRIC LOUIS CHOPIN, a citizen of the Republic of France, residing at Paris, France, have invented new and useful Improvements in Percussion-Drills, of which the following is a specification.

This invention relates to improvements in percussion drills, particularly such as described in my co-pending application Serial 10 No. 144,783, filed January 26, 1917, of which this is a divisional application.

It is the object of the invention to provide a detachable holder for the tool of such drills, permitting a quick exchange of the tools.

Another object of the invention is to effect improvements in the construction of the drill tool so that water may be injected to lay the dust and clean the hole made by the bit.

With these and other objects in view which 20 will be more fully explained in the specification, the tool holder includes certain novel construction, combination and arrangement of parts which will be hereafter described in detail, and specifically pointed out in the 25 claims, reference being had to the accompanying drawings, in which:

Figure 1 is a longitudinal elevation of the drill with the holder for the tool according to the present invention.

Fig. 2 is a longitudinal section through that part of the drill receiving the tool.

Fig. 3 is a cross-section on line A—B Fig. 2, and

Fig. 4 is a cross-section on line C—D Fig. 2.

Fig. 5 is a detail elevation, showing the lugs of the ring in section and disclosing the engagement of one of the securing rods with such lugs.

To the lower end of a drill 1 with handle 2, body 3 and rods 4 connecting the cover of the drill 1 with the body 3, is secured the holder for the tool 10. The rods 4 at this end of the drill form a T-shaped element, and 45 each of them engages between stops 7' provided on a ring 7 which by means of a washer 8 of suitable material positions the sleeve 9 of the tool 10. Said washer cushions the sleeve 9. The said sleeve 9 is provided 50 at its inner end with outer and inner annular grooves 12, 11, respectively, which extend therearound, and prevent idle shocks of the piston from producing a bur on the sleeve which might cause the sleeve to jam in the 55 bore of the body.

The holder proper for the tool 10 comprises a collar 14 which is made in two parts connected together in a diametrical plane which separates the lugs 15 and 16, the former of which has the form of a hook, 60 while the lug 16 has the shape of a boss to form a button with a shoulder.

The inner end portion of the tool is arranged for sliding movement in the sleeve and is of cross sectional polygonal form, 65 so that the tool fits loosely in the sleeve. Such construction minimizes friction and greatly facilitates detachment of the tool from the drill body when this is desired.

The links 17 and 18 which connect the ring 70 7 to the collar 14 are suitably bent wires as shown in Fig. 1.

The stops 7' are forced into the eyelets formed on the links 17 and 18, and then the lugs 15 are introduced into the bottom eyelet 75 of the link 17, and a hammer blow drives the two halves of the lugs 16 into the lower eye of the link 18. A hammer blow in the opposite direction is sufficient to disengage this link from the said lug-halves 16. 80

A material 19 such as leather or rubber, is inserted into the collar 14 in order to soften the shocks of the shoulder of the tool 10 on the same.

The tool has a shoulder 24 extending there-around at a point between the guiding collar 14 and the ring 7 and also has a bore leading to the outer end of the tool. A split collar 27 is arranged around the shoulder of the tool and has its ends connected together by 90 means of a cotter 28. A radial duct 25 extends from the bore of the tool to the face of the shoulder, and the split collar is formed with means for the attachment of a flexible hose 29 thereto, to enable a cleaning fluid to 95 be admitted to the bore of the tool.

What I claim is:

1. A drill including a body, a cover therefor, a ring below the body, two pairs of lugs upon opposite sides thereof, bolts formed 100 with T-shaped heads engaged by said lugs, their opposite ends being secured to the cover, a collar below the ring, a pin extending outwardly from each side of the said collar, and a bent wire extending between 105 the lugs and pin respectively.

2. A drill including a body, a cover therefor, a ring below the body, two pairs of lugs upon opposite sides thereof, bolts formed with T-shaped heads engaged by said lugs, 110

and having their ends secured to the cover, a collar below such ring, a split pin projecting from said collar, and a bent wire extending between the said pin and lugs respectively.

5. 3. A percussion drill including a sleeve, a ring on which the sleeve bears, said ring having two pairs of lugs on opposite sides thereof, a tool slideable within said sleeve, a collar embracing said tool and positioned below said ring, such collar comprising two half sections provided with outwardly extending portions, and a resilient loop member upon each side of the ring and collar, having its two ends secured to the lugs of the ring, its lowermost portion engaging the outwardly extending portion of the collar whereby to hold said collar in applied position.
10. 4. A percussion drill including a sleeve having inner and outer annular grooves at its inner end, a tool fitting loosely within said sleeve, a ring around said tool and bear-

ing against the outer end of the sleeve, means to secure the ring, a guiding collar for the 25 tool, and means to detachably secure said guiding collar to said ring.

5. In a percussion drill, the combination of a drill body, a sleeve in the outer end of the body, a ring bearing against the outer 30 end of the sleeve, means to detachably secure the ring in place, a tool having a portion arranged for movement in the sleeve, a collar around the tool, spaced from the ring and comprising a pair of diametrically separable 35 members, and means to connect the collar to the ring and to hold the collar in place, said connecting and holding means also securing the members of the collar together.

In testimony whereof I affix my signature 40 in presence of two witnesses.

ALBÉRIC LOUIS CHOPIN.
